UNITED STATES PATENT OFFICE.

JOHN C. SHOTTON, OF LAKewood, OHIO.

DENTAL CASTING DEVICE AND PROCESS.

Application filed July 30, 1923. Serial No. 654 633.

To all whom it may concern:

Be it known that I, JOHN C. SHOTTON, a citizen of the United States, residing at Lakewood, in the county of Cuyahoga and State of Ohio, have invented certain new and useful Improvements in Dental Casting Devices and Processes, of which the following is a specification.

The present invention relates to a process of and apparatus for making dental castings, and the object of the invention is to provide a simple and efficient means whereby the molten gold or metal can be readily caused to enter the cavity of a mold.

Dental castings are usually made of some precious metal, such as gold, and it has been found necessary to provide some means for forcing the molten gold to flow through the comparatively small sprue opening and enter the cavity of the mold. This has been accomplished in various ways, as by the use of centrifugal force or by means of air pressure. The centrifugal machines which have been devised for this purpose are of an expensive and complicated character, while in many of the devices using air pressure it is difficult to keep the air pressure under the accurate control which is necessary to obtain satisfactory castings.

The object of the present invention has been to eliminate all of the objectionable features of the centrifugal and air pressure devices and to provide an extremely simple process and apparatus whereby the molten metal is caused to flow into the cavity of the mold under a pressure which is caused by the generation and expansion of gaseous mediums, so that there are no violent stresses which might rupture the mold and splendid castings can be obtained without difficulty.

For a full understanding of the process and apparatus embodying the invention, reference is to be had to the following description and accompanying drawings, in which,

Figure 1 is a side elevation of a dental casting device which is constructed in accordance with the invention, portions being broken away and shown in section to illustrate more clearly the details of construction.

Figure 2 is a top plan view of the device.

Corresponding and like parts are referred to in the following description and indicated on all of the views of the drawings by like reference characters.

Referring to the drawings which illustrate one of many possible mechanical constructions which are adapted to be used in practicing the invention, the numeral 1 designates a base member upon which the mold A rests. The mold is of the usual form and includes a metal ring 2 which is filled with a suitable investment 3, in which there is a cavity 4 which has been formed by a wax pattern and which is of the exact size and shape of the desired metal casting. There is the customary depression 5 formed in the top of the investment and a comparatively small sprue opening 6 leads downwardly from the base of the depression to the cavity.

The customary way of forming these molds is to make a wax impression or pattern of the cavity in the tooth which is to receive the gold casting. This wax pattern is placed upon the point of a pin by means of which it is supported in the ring 2 while the investment 3 is poured into position. After the investment has hardened the pin is removed and the mold is subjected to a sufficient amount of heat to completely remove or burn out the wax, thereby leaving the cavity 4 and the comparatively small sprue opening 6 leading downwardly thereto from the depression 5. The foregoing is the conventional way of forming a mold, although so far as the present invention is concerned the mold can be formed in any desired manner.

In forming a casting a quantity of molten gold or other metal 7 must be placed in the depression 5 and some means utilized for causing the molten metal to flow through the sprue opening 6 and enter the cavity before the metal cools and hardens. To facilitate this operation the mold is, of course, heated so that the molten metal will not harden when it first comes into contact therewith.

According to the present invention a flared cup member 8 is utilized, said cup member being provided with a suitable handle 9. In the present instance the handle is connected to the back of the cup member by means of a stem 10 which is formed at an intermediate point in its length with an annular enlargement 11 which is useful in handling the cup member.

The cup member is partially filled with a plastic substance 12 and the mouth of the cup member is formed with an inturned flange 13 which is of assistance in keeping

the plastic substance in proper position within the cup member. The plastic substance contains some material or ingredient which, when subjected to the action of heat, will be volatilized or decomposed to produce a gas. One form of plastic substance which can be used is a mixture of fuller's earth and glycerine in the proper proportions to provide a putty-like substance.

10 After the molten metal has been placed in the depression 5 at the top of the heated mold A, the flared cup member 8 is quickly clapped upon the top of the mold, assuming the position indicated by Figure 1 of the drawings. The upper edges of the ring 2 penetrate the plastic substance 12 and cooperate therewith to provide a substantially gas tight connection between the cup and the top of the mold. The chamber B which

15 is thus provided over the top of the mold is effectively sealed and cut off from the atmosphere, and the heat of the molten metal and hot mold serve to volatilize and decompose the glycerine of the plastic material

20 to form a gas. The air which was in the chamber B is also heated and caused to expand, and the resultant pressure caused by the expansion of the heated air and the production of a gas by the heating of the glycerine forces the molten metal 7 downwardly

25 through the sprue opening 6 into the cavity 4. No delicate or difficult manipulations are required, and the molten metal is forced downwardly into the cavity of the mold by a gaseous pressure and without any sudden jars or violent stresses such as might tend to rupture the mold.

30 While I am not certain as to the exact reaction or change which takes place when the glycerine is heated, it is probable that the glycerine is either vaporized without decomposition or decomposed into acrolein (C_3H_4O) and water, thereby producing a considerable quantity of gas which is under

35 sufficient pressure to force the molten metal into the mold. Any water which may result from the decomposition of the glycerine may also be vaporized and a certain amount of steam produced thereby. I am not certain as to exactly what reaction, if any, takes place when the glycerine is heated.

40 If the glycerine is pure it may volatilize without undergoing decomposition, although if it is more or less impure it may be partially or wholly decomposed, and in that event it is probable that it decomposes according to the following formula:

45 While glycerine is specifically mentioned

as a substance which has given satisfactory results and can be used, it will be understood that any other substance which will produce a gas when subjected to the heat of the molten metal and mold can be used and that any other device for forming a closed chamber over the mold can be utilized. The process of forming these castings by providing a closed chamber over the mold and then generating a gas in the closed chamber to produce a pressure for forcing the molten metal into the mold is believed to be broadly new, and it will be understood that I do not restrict myself to the particular construction shown on the drawings or to the particular substance for generating a gas in the chamber, since many modifications of the apparatus and variations in the manner of carrying on the process are possible without departing from the spirit of the invention and within the scope of the claims. The term gas as used in the claims is intended to cover steam and vapors or their equivalents, as well as the more permanent gaseous mediums.

Having thus described my invention what I claim as new and desire to secure by Letters Patent is,

1. A dental casting device, including a flared cup member adapted to be fitted upon a mold to provide a closed chamber, the inclined sides of the cup member enabling it to be fitted upon different sizes of molds, and a plastic lining for the cup member which engages the edges of the mold to provide a gas tight joint therewith, said plastic material including an ingredient which will be acted upon by the heat of the mold and molten metal to generate a gas and produce a pressure to force the molten metal into the mold cavity.

2. A dental casting device including a flared cup member formed with a substantially conically shaped cavity and adapted to be fitted upon a mold to provide a closed chamber, the end of the cup member being provided with an inwardly extending marginal lip, and a plastic lining for the cup member which is held in position by the said lip and which engages the edges of the mold to provide a gas tight joint therewith, the conical formation of the cavity enabling the cup member to fit various sizes of molds and the plastic material including an ingredient which will be acted upon by the heat of the mold and molten metal to generate a gas and produce a pressure to force the molten metal into the mold cavity.

In testimony whereof I affix my signature,

JOHN G. SHOTTON.
